United States Patent [19]

Takahashi et al.

[11] Patent Number: Des. 285,923

[45] Date of Patent: ** Sep. 30, 1986

[54] ARITHMETIC OPERATION CONTROL
MACHINE FOR ELECTRONIC COMPUTERS

[75] Inventors: Tsuneo Takahashi, Kawagoe;
Takaharu Andoh; Keiichi Washizuka,
both of Yokohama, all of Japan

[73] Assignee: Tokyo Shibaura Denki Kabushiki
Kaisha, Japan

[**] Term: 14 Years

[21] Appl. No.: 586,993

[22] Filed: Mar. 7, 1984

[30] Foreign Application Priority Data

Sep. 20, 1983 [JP] Japan 58-40707

CLAIM

The ornamental design for an arithmetic operation control machine for electronic computers, substantially as shown.

DESCRIPTION

FIG. 1 is a front, top, and right side perspective view of an arithmetic operation control machine for electronic computers showing our new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and

FIG. 7 is a bottom plan view thereof.

FIG. 1

FIG. 2

FIG. 3

FIG. 4

FIG. 5

FIG. 6

FIG. 7
